UNITED STATES PATENT OFFICE.

ADOLPH O. GOODYEAR, OF EAST CLEVELAND, OHIO.

DESIGN FOR A BRIDGE FOR VIOLINS OR SIMILAR STRINGED INSTRUMENTS.

43,358.

Specification for Design.

Patented Dec. 24, 1912.

Application filed October 10, 1912. Serial No. 725,056. Term of patent 14 years.

To all whom it may concern:

Be it known that I, ADOLPH O. GOODYEAR, citizen of the United States, residing at East Cleveland, in the county of Cuyahoga and State of Ohio, have invented a new, original, and ornamental Design for a Bridge for Violin or Similar Stringed Instrument, of which the following is a specification, reference being had to the accompanying drawing, forming part thereof.

Figure 1 is a plan of a bridge for violin

or similar stringed instrument, showing my new design. Fig. 2 is an edge view. Fig. 3 is a top view.

I claim:

The ornamental design for a bridge for violin or similar stringed instrument, as shown.

ADOLPH O. GOODYEAR.

Witnesses:

JOHN A. BOMMHARDT,
GERTRUDE M. WERNER.
